UNITED STATES PATENT OFFICE.

DAVID GLOVER, OF CASS TOWNSHIP, SCHUYLKILL COUNTY, PENNSYLVANIA.

SAFETY-CAGE FOR COAL-SHAFTS.

Specification of Letters Patent No. 24,296, dated June 7, 1859.

To all whom it may concern:

Be it known that I, DAVID GLOVER, of the township of Cass, in Schuylkill county, State of Pennsylvania, have invented a new and useful safety cage or carriage for use in perpendicular shafts, intended to prevent the falling of the cage when the connection between the hoisting power and the cage shall by the breaking of the chain or rope used in hoisting or by any other means be destroyed or the power cease to operate; and I do hereby declare that the following is a full, clear, and exact description of the construction and operation of the same, reference being had to the annexed drawings, making a part of this specification, in which—

Figure No. 1, is a perspective view, Fig. No. 2, a side view of the cage, showing the position it assumes when the rope or chain used in hoisting has been broken, Fig. No. 3, is a plan of the bottom of the cage, and shows side view of hinge, Fig. No. 4, is a plan of top of the cage.

In shafts sunk for the purpose of raising coal, or other minerals where the cars used in the drift, or adit are elevated to the surface, the car to be hoisted is for this purpose run upon a cage, or carriage at the bottom of the shaft, and secured thereon by either a hook, or bolt, or by any other means found most convenient, and this cage, (which is kept in position while ascending, or descending the shaft by guides "A," "A" Fig. 1, running from the top to the bottom of the shaft, the rest of the cage running perfectly free of the shaft sides) is then elevated with the car so fastened on it to such height as is desired, where it is caught on rests made for the purpose, and the car removed till it is ready to be returned to the bottom. The cage heretofore in common use is generally made of wood or iron of the form, and construction seen in the whole of Fig. No. 1, in which the top rail and bottom sill are of one continuous piece, and make the whole cage one stiff frame; the guides "A," "A" playing between the side pieces or strips "B" "B" Fig. 1, which are securely bolted to the rails and sills of the cage. When in the passage, (up, or down,) of this cage the rope, or chain used in hoisting breaks, or by any means the connection between the hoisting power and the cage is destroyed, there is nothing to prevent its dropping down the shaft, and it necessarily falls to the bottom with great

violence totally destroying both cage and car.

The cage, or carriage for which a patent is desired, instead of being one stiff frame of the form represented by the whole of Fig. No. 1, is made in two distinct sections, or separate parts. These sections, or separate parts are each of the same shape, and are precisely of such form as is made by cutting the common cage of the form represented by the whole of Fig. 1, by a plane immediately through the center of the guides "A" "A" Fig. 1. These two separate sections, or parts are fastened together only at the top of the bottom sill by two hinges "C," "C" as seen in the plan of the bottom of the cage in Fig. 3. These hinges are of the form C Fig. 3, or any shape that will permit the separate parts of the cage to open at the top rail and hold the top of the bottom sills firmly together. The ends of these sills immediately under the hinges are cut off at such an angle as to leave them about four inches apart at the bottom. At the top the ends of these sections are left entirely separate. The ends of the top rails are left square so as to fit evenly together.

To prevent any lateral play, and to hold the top rails in line when the cage is in use, four pieces of iron, or wood of the shapes F, F, Fig. No. 4 are bolted on the top of the top rails in the manner seen at "f," "f" Fig. 4, and when the cage is in use, and the top of the separate sections drawn together they fit closely in each other, thus preventing lateral motion, and keeping the cage stiff, and firm.

The chain, or rope used in hoisting is connected with the cage by four small chains which are fastened at the points "M" "M," Fig. 1, to the cage by iron bolts as seen in the drawing, or by any other means found most convenient, and meet together in the ring "E" Fig. 1, to which the chain or rope is fastened.

The bottoms of the sills at "L" Fig. 1, are shod with strong pieces of iron "h," "h," of the shape H Fig. 1, (which is a plan of them) which pieces of iron are notched into the sills, and strongly bolted to them. They extend out over and cover the bottoms, or lower ends of the side pieces, or strips "B," "B," coming as closely to the guides as possible without creating friction. The lower angle of the ends of these iron pieces, is, next to the guides, made slightly acute to

ward the guides so as to present somewhat of a cutting edge, which if pressed against the guides with any force will at once penetrate or nip them.

- 5 When this cage, (now being described) and made of the two separate sections as before set forth, rests on the bottom of the shaft ready for use, the ends where the section is made at the guides "A" "A" fit closely together and the cage presents, except the portion cut off of the ends of the bottom sills precisely the appearance of the common cage. And when the rope, or chain used in hoisting is stretched, and the cage is passing up, or down the shaft it maintains the appearance, and form of the common cage, and operates no way different from it. When however the rope, or chain used in hoisting breaks, or the cage is by any means suddenly disconnected from the hoisting power, or the power ceases to operate the separate sections of the cage, by the force of their own gravity will separate at the top, and being held together at the top of the bottom sill by the hinges "C" "C" these separate sections act as a lever to force the iron shoes on the bottom of these sills, and the pieces "B" "B" into the guides of which they take such a hold as to prevent the cage from falling, and it is held firmly in the shaft as seen in Fig. No. 2 till the rope, or chain can be mended and the power

applied when it is immediately ready for use.

If found necessary to give greater quickness of action to the opening of the cage at the top on the breaking of the rope, or chain, &c., springs "S," "S," as seen in Figs. Nos. 1 and 2, can be so arranged as to assist the action of gravity in opening the separate sections at the top.

Having thus described the construction and operation of my safety cage for use in shafts, what I claim as my invention and desire to secure by Letters Patent is—

The construction of the cage in two separate sections, separated at the guides, and so connected by hinges at the top of the bottom sill, that when the rope, or chain used in hoisting breaks, or the power ceases to operate, the cage shall open at the top, where the sections are joined, and the height and weight of each section, shall operate as a lever and weight to force the iron shoe on the ends of the sills, and pieces "B" "B" powerfully against, and into the guides, and by this means entirely prevent the dropping of the cage, and car down the shaft.

Signed in the presence of two witnesses this 6th May 1859.

DAVID GLOVER.
